UNITED STATES PATENT OFFICE.

JOSEPH USHER, OF WEST ALBANY, NEW YORK.

IMPROVEMENT IN DISH-WASHING MACHINES.

Specification forming part of Letters Patent No. 135,176, dated January 21, 1873.

To all whom it may concern:

Be it known that I, JOSEPH USHER, of West Albany, in the county of Albany and State of New York, have invented a new and useful Improvement in Dish-Washing Machine, of which the following is a specification:

Figure 1 is an end view of my improved machine. Fig. 2 is a detail vertical cross-section of the same taken through the line *x x*, Fig. 3. Fig. 3 is a front view of the same, partly in section, through the line *y y*, Fig. 2.

Similar letters of reference indicate corresponding parts.

My invention has for its object to furnish an improved machine for washing dishes, which shall be so constructed as to wash the dishes quickly and thoroughly, and which shall at the same time be simple in construction and convenient in use; and it consists in the combination of the frame, the pivoted lower grates and their springs, the pivoted upper grates and their lock-bars, and one or more vertical partition-grates with each other for receiving and holding the dishes; and in the combination of the ventilated base-box and ventilated drawer with the outer box, the pivoted case, and the dish-frame and its attachments, as hereinafter more fully described.

A is a box of suitable size, according to the amount of work to be done. The box A is provided with a hinged cover, B, and with a pipe, C, for the waste water to escape through into any convenient receptacle. The box A rests upon the rabbeted edges of the box D, which thus serves as a stand. The box A is made with ventilating-holes, and with its front side open to receive the drawer E, which is also made with ventilating-holes in its sides. The box D and drawer E are made of such a size that the said drawer may contain one or more of the dish-frames, hereinafter described. F is a box or case lined with tin, zinc, or other suitable sheet metal, and provided with a hinged cover, G, also lined with tin, zinc, or other suitable sheet metal, and provided with rubber packing H to make the said box watertight when its cover is closed. The cover G is secured in place, when closed, by hooks, as shown in Fig. 2. I is a frame fitting snugly into the case F G. In the lower part of the frame I is placed a number of wire grates, J,

which are pivoted at one end of their side edges to the lower-side bars of the frame I, and their free edges rest upon coiled wire springs K, which rest upon and are secured to the bottom bars of said frame I. In the upper part of the frame I are placed a corresponding number of similar wire grates, L, which are pivoted at one end of their side edges to the top side bars of the frame I, so that the said grates L may be turned up to allow plates, platters, and other wide and shallow dishes to be inserted between the said upper and lower grates, as shown in dotted lines in Figs. 2 and 3. The upper grates L are secured in place when closed down upon the dishes by pivoted bars M, which have a number of notches formed in the upper part of their forward edge to hook upon the free edges of the upper grates L and hold them down upon the dishes, the yield of the springs K allowing the said upper grates to be hooked down with sufficient closeness to hold the dishes securely. One or more spaces or compartments may be formed to receive smaller dishes by a vertical wire grate or screen, N. The bottom of said compartments may be formed of a perforated sheet-metal plate arranged in the same manner as the lower grates J. To the ends of the case F G are attached gudgeons O, which pass through and revolve in bearings in the ends of the box A. One or both the gudgeons O are squared upon their ends to adapt them to receive a crank for revolving the case F G and its contents. One or both the gudgeons O may be provided with a notched slide, P, to be slipped upon the ends of the said gudgeons to prevent the case F G from turning while putting in and taking out the frame I. In using the machine, the dishes to be washed are arranged and secured in the frame I, and the said frame I is placed in the case F. A quantity of water, or soap and water, are then placed in the case F, and the door G is closed and secured. The case F G and its contents are then revolved a few times—first in one direction and then in the other—which quickly cleans the dishes. The door G is then unfastened, and the case F G is turned, allowing the water to run off. A quantity of clean water is then poured into the case F, and the dishes are rinsed in the same manner as they were washed, after which the rinsing-water is emptied out in the same manner as the

washing-water, and the frame I and the dishes are removed and placed in the drawer E. When the dishes are to be used they are removed from the frame I and wiped with a clean cloth.

Having thus described my invention, I claim as new and desire to secure by Letters Patent—

1. The portable frame I divided into one or more compartments, lower movable pivoted grates J, springs K, upper movable pivoted grates L, pivoted hook-bars M for hooking on the upper grates L for the purpose of securing

and holding the dishes, substantially as herein shown and described.

2. The combination of the revolving water-tight case F G and its attachments and frame I with its internal arrangements, with outer chest A, ventilated box D, and ventilated drawer E, substantially as herein shown and described, and for the purposes set forth.

JOSEPH USHER.
